UNITED STATES PATENT OFFICE.

SAMUEL OLDHAM, OF PHILADELPHIA, PENNSYLVANIA, ASSIGNOR TO GEORGE OLDHAM AND SON COMPANY, OF BALTIMORE, MARYLAND, A CORPORATION OF PENNSYLVANIA.

PNEUMATIC TAMPER.

Application filed November 3, 1920. Serial No. 421,586.

To all whom it may concern:

Be it known that I, SAMUEL OLDHAM, a citizen of the United States, residing at Philadelphia, in the county of Philadelphia and State of Pennsylvania, have invented 5 certain new and useful Improvements in Pneumatic Tamers, of which the following is a specification.

This invention relates to improvements in 10 pneumatic tampers and has particular reference to an improved construction of portable tamper that may be held, operated and entirely controlled by one operator.

One object of the invention is to provide 15 an improved means for controlling the passage of the actuating fluid to the tool whereby the control device may serve the double purpose of handle and control.

Another object is to provide an improved 20 tool whereby the means utilized to hold the tool to its work may also serve to control the operation of the plunger-hammer so that when the holding pressure is relieved the operation of the tool may be stopped without 25 requiring the manipulation of another or separate structure or valve.

A further object of the invention is to provide an improved arrangement of handle and pressure control device with means co- 30 acting therewith to enable the same to be locked in the operating position.

I am aware that various forms of fluid-actuated tools have heretofore been devised 35 which employ cylinders with handle-extensions at one end or with a plurality of handles one extending at right angles to a cylinder and another carried by or extended from one end of the cylinder. As an example of these prior devices I call attention to 40 U. S. Patents 712,843—796,703 and 1,147,660.

In the Patents 796,703 and 1,147,660 each tool has a cylinder with a handle-extension at one end thereof and the extension in each instance has two handles which project at 45 right angles with respect to each other.

In my improved device I provide a horizontally-projecting device which serves the purpose of a combined valve-control lever and a handle.

50 My invention is illustrated in the accompanying drawing, wherein,—

Fig. 1. shows the improved tool in longitudinal sectional elevation.

Fig. 2. illustrates an enlarged sectional de-

tail through the tool at the control device,— 55 the section being taken on a line at right angles to that in Fig. 1.

Fig. 3. shows a cross-sectional detail through the tool as the same would appear if cut on the line 3—3 of Fig. 2. 60

Fig. 4. illustrates an enlarged sectional detail through the lower end of the cylinder or barrel and the retaining devices to hold the working-tool in place, and

Fig. 5. shows in perspective, one of the 65 detached bushing sections that are retained in the end of the barrel and through which the working-tool reciprocates.

In the drawing the numeral 6 designates the cylinder or barrel of the tamper having 70 a chamber 7 therein in which a piston 8 is longitudinally reciprocable.

A passage 9 is provided in the wall of the barrel and communicates with the cylinder whereby to conduct fluid, under pressure, 75 such as compressed air to the chamber 7 to operate the piston.

The present invention has nothing whatever to do with the construction or operation of the piston as this is old and well-known in the art of fluid-actuated tools and the present disclosure is simply illustrative of a form of cylinder and piston.

To one end of the cylinder there is bolted a head 10, which latter closes the end of the 85 chamber 7. This head 10, is provided with a central valve-chamber 11, into the lower end of which there is screwed a plug 12, so that the valve-chamber is entirely cut off from the upper end of the cylinder chamber 90 7 by said screw-plug.

The valve-chamber has an upper reduced portion 13, from the side of which there leads a passage 14, which extends downwardly to and communicates with the passage 9 in the wall of the barrel so that communication between the valve-chamber 11 and the cylinder or barrel-chamber 7 may be established or cut-off according to the position of a valve in said valve-chamber as will 100 now be described.

A valve device is located in the valve-chamber which device has a valve head 15, with a lower guide stem 16, that is guided in a central passage in the plug 12, and an 105 upper stem-part 17 which carries a head 18, that fits the upper reduced portion 13 of the valve-chamber. When the valve is in the

lowered or depressed position, as shown in Figs. 1 and 2, the head 18, at the upper end thereof, has position in a horizontal plane above the upper end of the side passage 14, 5 while the valve-head 15 is depressed below and uncovers a seat 19 that is located at the entrance to the upper reduced portion.

A spring 20 is coiled about the lower guide stem 16 and, when the valve is depressed and 10 in the open position, this spring is compressed between the valve-head 15, and the plug 12, but said spring is sufficiently strong to lift the valve and its actuating devices when pressure on the latter is removed, as 15 will now be explained.

The head 10, has a vertical stem into which the reduced portion 13 of the valve-chamber projects and the upper end of this reduced portion opens into the bottom side 20 of a cross-slot 21 which latter extends horizontally across said stem, as best shown in Fig. 2 of the drawing. Horizontally-projecting lugs 22, are provided on the stem at opposite sides of the slot so that an actuating 25 lever 23, may extend through the slot and have one end thereof pivoted by means of a cross-pin 31 that extends through said end and also through the lugs 22.

The lower edge of this actuating lever 23, 30 projects over and seats upon the upper end of valve-stem head 18 so that by depressing or raising the said lever a corresponding downward or upward movement may be imparted to the valve structure.

35 The downward movement of the lever and valve structure is obviously effected by manually compressing the spring 20 and the upward movement is automatically effected by air and spring-pressure when manual pressure on the lever is released,—the spring, 40 as heretofore recited, being sufficiently strong to lift both the valve structure and the lever.

To facilitate the operation the lever has a 45 free end 24, which in the present instance is broadened and slotted so it may be readily grasped by the hand of the operator and pulled upwardly to seat the valve or pushed downwardly to unseat said valve.

50 By reference to Fig. 1 of the drawing it will be seen that a fluid-pressure supply port 25, is provided in the head 10, which opens into the chamber 11, beneath the valve-seat 19, so that when the valve-head 15, is 55 pressed down the supply port and chamber 11 will be in communication with the passages 14 and 9 that lead to the cylinder.

It is to be understood that any upward 60 pull on lever-end 24 or the mere release of said end by the removal of the hand of the operator will at once permit the valve to move upwardly and engage the seat 19, thereby automatically cutting off the fluid-pressure to the cylinder and stopping the 65 operation of the piston 8.

At times it may be desirable to cause the piston to continue operation while the hand of the operator is removed from the free end 24 of the lever and to enable this to be done I provide a sliding lock device 26 on the lever with a lug 27 thereon so that by moving the lock on the lever toward the slot 21, the lug 27, will become interposed between the upper edge of said slot and the upper side of the lever and thus hold the lever 75 and valve down against the action of the spring and thereby keep the valve 15, unseated.

By reference to Figs. 2 and 3 of the drawing it will be noted that the lever 23, is provided with a cross-passage 28 in which a spring-pressed ball 29, is confined so as to slightly project at one side and form a yielding stop to engage a vertical edge of the sliding lock and hold the same in either the unlocked or the locked position.

The extreme upper end of the head stem is provided with a suitable handle 30, which may be grasped by the operator during the handling, or the operation of the tool.

The lower end of the cylinder or barrel 6 has a central chamber 32 therein with guide-bushing 33, in the upper end thereof and at the entrance to said chamber there is provided a split or two-part bushing 34, which has a stop-shoulder 35, around its exterior to limit its inward movement into said chamber 32. The relative positions of these two bushings 33 and 34 are such as to leave a space between their adjacent ends in the chamber 32, so that the tool 36 which receives the blow of the piston 8, may be guided by said bushings and may be limited or restricted in its longitudinal movement by means of an enlargement 37, thereon which 100 may travel between said two bushings.

A coiled spring 38 encircles the outer circumference of the lower barrel-end which is provided with a spiral groove or thread to receive it and the lower end of this spring coils about the split bushing 34, beneath the shoulder 35 thereon so as to yieldingly hold the bushing in place but allow the same to yield longitudinally in case the enlargement 37 on the tool should make a long enough stroke to strike the inner end of the split bushing.

Having described my invention, I claim,—

1. In a fluid actuated tool, the combination of a cylinder; a reciprocating piston mounted therein; a working tool held in one end of the cylinder so as to be acted upon by the piston; a valve device controlling the passage of fluid to the cylinder; and a pair of handles for holding and positioning the tool, one of said handles being fixed with reference to the cylinder and the other of said handles being pivotally mounted and movable with respect to the cylinder, 130

said latter handle when moved in the feeding direction of the tool opening the valve to permit passage of fluid to the cylinder.

2. In a fluid actuated tool, the combination of a cylinder; a piston mounted for reciprocation therein; a working tool held in one end of the cylinder so as to be acted upon by the piston; a head attached to the opposite end of said cylinder; a valve device in said head to control the passage of fluid to the cylinder; and a pair of handles for holding and positioning the tool, one of said handles being fixed upon the upper portion of the head, and the other of said handles being movable with respect to the head, said latter handle when in one position opening the valve to permit passage of fluid to the cylinder.

3. A fluid-actuated tool comprising a cylinder containing a reciprocating piston, a working tool held in one end of the cylinder so as to be acted upon by the piston, a head at the opposite end of the cylinder said head being provided with a stem with a cross-slot therein,—said head also having a valve-chamber which opens into said cross-slot, a valve in said valve-chamber to control the passage of fluid to the cylinder and a lever movable in said stem-slot and engaging the valve said lever also serving as a handle for the tamper-tool.

4. A fluid-actuated tool comprising a cylinder containing a reciprocating piston, a working tool held in one end of the cylinder so as to be acted upon by the piston, a head at the upper end of the cylinder and provided with a stem with a rigid handle thereon, a valve device operating in the head for controlling the passage of fluid to the cylinder, a combined valve-actuating lever and handle carried by the stem for opening the valve by pressure on the lever while the tool is held to its work by the handles and means for closing the valve when the pressure on the lever is relieved.

5. A fluid-actuated tool comprising a cyl-

inder containing a reciprocating piston, a working tool held in the lower end of the cylinder so as to be acted upon by the piston, a head having a stem,—said head being located at the upper end of the cylinder and provided with a stem with a rigid handle thereon, a valve in the head for controlling the passage of fluid to the cylinder and a movable handle also mounted on the stem and located between the rigid handle and cylinder for operating the valve,—said handles enabling the operator to readily position the tool.

6. A fluid-actuated tool comprising a cylinder containing a reciprocating piston, a working tool held in one end of the cylinder so as to be acted upon by the piston, a head attached to the cylinder adjacent to the opposite end said head having a projecting stem with a rigid handle thereon, a valve device in said head to control the passage of fluid to the cylinder, a movable handle carried by the stem for actuating the valve and also serving along with the rigid handle, to press the tool to its work, and means for locking the movable handle in the position to keep the valve open.

7. In a power-actuated tool, the combination of a body; a tool carried thereby; power-actuated means located within the body to actuate the tool; controlling means for said power-actuated means; and a pair of handles for holding and positioning the body and tool, one of said handles being fixed with reference to the body at upper portion of the same and the other of said handles extending laterally from the body and being movable with respect to the body, said latter handle when in one position rendering said power controlling means effective to put the power-actuated means into operation.

In testimony whereof I affix my signature.

SAMUEL OLDHAM.
